UNITED STATES PATENT OFFICE.

ALPHEUS W. ALTORFER, OF PEORIA, ILLINOIS, ASSIGNOR TO ALTORFER BROS. COMPANY, OF EAST PEORIA, ILLINOIS, A CORPORATION OF ILLINOIS.

WASHING MACHINE.

Application filed November 27, 1922. Serial No. 603,538.

This invention has reference to washing machines and particularly to the domestic or household type machine.

The invention has for its principal object to combine in the oscillator tub type machine, the vacuum cup type machine; whereby the advantages embodied in oscillating and vacuum cup machines are contained in one machine.

10 This application discloses an improvement on the tub or container forming the subject matter of the application filed by me October 12, 1922, bearing Serial No. 594,019. In that case the cups, agitators, or pounders 15 are more in the form of an attachment and the walls of the container are constructed to receive the same. As herein disclosed, the vacuum cups are built in and preferably located in the head walls of the container, producing a simple and inexpensive 20 structure and yet obtaining substantially the same results as the structure referred to in said mentioned application.

That the invention may be more fully 25 understood, reference is had to the accompanying drawings, forming a part of the present invention, illustrating a preferred embodiment of the invention, in which:—

Figure 1 is a vertical cross-section 30 through a tub or container embodying my invention;

Figure 2 is a detail transverse section 35 through the vacuum cups, as the same would appear on the line 2—2 Figure 1, and

Figure 3 is a plan view in section looking 40 up into the vacuum cups, as the same would appear, if taken on the line 3—3 Figure 2.

Like characters of reference denote corresponding parts throughout the figures.

45 I have omitted all showing to the frame construction, except the part shown in dotted lines and designated A, and also the operating mechanism and parts connected therewith and with the tub or container, and 50 also the power unit, such as an electric motor, or other means. A complete disclosure of these elements have been shown in said pending application and may correspond thereto or be modified at the discretion of the manufacturer.

The tub or container 1 is preferably intended to be mounted so that it may be oscillated alternately in opposite directions. It is also preferably constructed of sheet 55 metal and includes the side walls 2 joined by

the curved preferably corrugated or ribbed rubbing wall 3 and the head or top walls 4. The head walls are spaced and receive in such space a central neck or inlet portion 5 of suitable contour, the opening 6 of which 60 is covered by a removable lid or cover, not shown. The head walls 4 on either side of the neck 5, are inclined slightly from the rubbing wall 3 to the point where they unite with the walls of the neck 5, see Figure 1, 65 and are provided with a plurality of closely spaced openings 8 to receive vacuum cups 9, of any suitable and preferred shape. And I prefer that the cups 9 shall be disposed without the body of the tub or container 70 projecting above the head or top walls 4 with their axes in upwardly converging relation and flangedly connected with said head or top walls through the openings 8, somewhat in the manner shown in Figures 1 75 and 2. As shown, there are preferably three cups on each side of the neck 5, but by such showing it is not intended to limit the number of cups, as I realize such an arrangement is capable of modification, and that 80 any number of cups on either side of the inlet to the tub or container may be provided and still be within the scope of the invention.

As in my pending application referred to, 85 there is shown on the bottom of the tub or container a partition or obstruction 10, being a sheet preferably bent into the form of an inverted U to provide a compartment; the walls having openings 11 therein for the 90 circulation of water in the tub or container, and for the passage of water to a drain pipe, not shown, when it is desired to drain the tub.

In operation, the vacuum cups will act 95 on the water, as the tub is oscillated, first in one direction and then in the opposite direction, and the water forcing the air out of the cups into the water and through the fabrics will result in a cleansing of the fabrics. The oscillation of the tub will move the clothing or fabrics toward and away 100 from the cups, the cups returning before the water and clothing or fabrics can recede and act to further agitate the same and forcing air therein and therethrough to facilitate in the cleansing action. The partition or obstruction 10 not only assists in the agitation of the water to force the same 105 through the clothing or fabrics, but also 110

acts to keep the clothes or fabrics in agitation and to change the position thereof within the container or tub. Furthermore, the use of vacuum cups in an oscillatory tub 5 or container have a suction effect on the clothing or fabrics as they are moved with the volume of water to the cups, and such suction will act to momentarily hold or retard the fabrics as the water falls away due 10 to the alternate action of the tub or container, and as the water falls or moves away it will pass down through the clothing or fabrics further facilitating the cleansing operation.

What I claim is:—

15 A tub for washing machines having spaced downwardly and inwardly inclined head walls adjacent its outer sides and an upwardly extending inlet portion disposed in the space between the head walls, and 20 vacuum cups connected to the inclined head walls and projecting upwardly thereabove and exteriorly thereof and having their axes inclined upwardly in converging relation.

25 In witness whereof, I have hereunto affixed my hand this 25th day of November, 1922.

ALPHEUS W. ALTORFER.
